[57] CLAIM

The ornamental design for a newspaper stand, as shown and described.

DESCRIPTION

FIG. 1 is a perspective view of a newspaper stand showing my new design.

FIG. 2 is a side elevational view thereof.

FIG. 3 is a top plan view thereof.

Side elevational views taken from the remaining three sides are identical with the view of FIG. 2. The bottom of the stand is plain and unornamented.
